UNITED STATES PATENT OFFICE.

WILLIAM MOORE, OF LONG ISLAND CITY, NEW YORK.

COMBINED SQUARE, PLUMB, AND LEVEL.

SPECIFICATION forming part of Letters Patent No. 596,818, dated January 4, 1898.

Application filed February 24, 1897. Serial No. 624,784. (No model.)

To all whom it may concern:

Be it known that I, WILLIAM MOORE, of Long Island City, in the county of Queens and State of New York, have invented a new and 5 Improved Combined Square, Plumb, and Level, of which the following is a full, clear, and exact description.

The object of the invention is to provide a tool especially adapted for the use of bricklayers and masons in which will be combined a square, a plumb, and a level, the tool being so constructed that it is possible to use it upon work which is out of the perpendicular for leveling the same, and, furthermore, whereby 15 an arm may be projected from the body of the tool at any desired angle thereto and held in the position to which it is adjusted, the arm, together with the body of the tool, when one is at right angles to the other, constituting a regular carpenter's square.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a longitudinal vertical section 30 through the improved tool, showing the arm adapted as a square in position for use. Fig. 2 is a plan view of the tool with the aforesaid arm contained within the body of the tool. Fig. 3 is a side elevation of the tool. Fig. 4 is a vertical transverse section taken practically on the line 4-4 of Fig. 3; and Fig. 5 is a detail side elevation of the casing in which the spirit-level is contained, which casing is adapted to have rotary movement in the body 40 of the tool.

The body A of the tool is like that of the body of an ordinary level and may be of any desired dimensions and made of any approved material. Ordinarily near one end of the 45 body a vertical recess 10 is made, extending from the top downward, the bottom of the recess being of cylindrical shape. Within this recess a ring-casing 11 is mounted to turn, the ring-casing being provided with a level- 50 glass 12, which is bent upon itself to form,

preferably, three members which are at angles to one another, all of the members being exposed for a portion of their length at the opening in the ring-casing, as shown in Fig. 5.

Between the ends of the level-glass a knob 55 or handle 13 is secured, by means of which the ring-casing is turned in its seat. A spring 14 extends across the upper portion of the opening 10, engaging with the top of the ring-casing, and above this spring a bar 15 is located, having a central threaded aperture, while above the bar and the spring a face-plate 16 is countersunk in the top of the body of the tool.

A set-screw 17 is held to turn loosely in 65 the face-plate 16, being passed through the threaded opening in the guide-bar 15, which is preferably downwardly arched, and the lower end of the said screw engages with the spring 14, whereby the spring may be forced 70 to such contact with the ring-casing as to prevent said casing from turning after it has once been adjusted. Under this construction the set-screw 17 does not wear on the casing and a maximum of bearing-surface is 75 obtained. At the same time a quick relief is provided for the ring-casing when the adjusting-screw is carried in an outwardly direction.

At the opposite end of the body of the tool, in its top portion, a longitudinal slot 18 is made, 80 having a vertical direction. The side walls of this slot 18 are preferably protected by metal plates 19. At the outer end of the slot 18 a square arm or blade 20 is pivoted, the pivot-pin 22 of the blade or arm passing through a 85 polygonal foot-section 21. The pivot-pin 22, which is passed through the body of the tool from side to side, is provided with a countersunk head at one end and a countersunk nut 23 at the opposite end, as is shown in Figs. 2 90 and 4. A spring 24 has bearing against the polygonal head of the square arm or blade 20, being adapted to engage with one of the facets of the said head. The inner end of the spring 24 is pivoted near the inner end of the slot 18 95 by a suitable pin 25, which usually extends through from side to side. The tension of the spring 24 may be increased or diminished through the medium of an adjusting-screw 26, which is entered at the bottom of the body of 100

the tool, the head being contained within a suitable recess, and the inner end of the adjusting-screw, which is passed through the nut 27, is in engagement with the bottom of the spring 24 at a point near its center.

A second adjusting-screw 28 is employed, similarly situated to the adjusting-screw 26. The adjusting-screw 28, however, engages with the bottom of the spring 24 at a point immediately below the head of the square blade or arm 20, as shown in Fig. 1. This latter adjusting-screw 28, which may be passed also through a nut 29, serves to hold the square blade or arm rigidly in the position to which it has been adjusted and will accomplish its object effectually whenever the spring is in engagement with a facet on the said head; but when it is necessary to adjust the square blade or arm 20 in a manner which will bring a corner of the head in engagement with the spring it is necessary that fastening devices should be employed auxiliary to the adjusting-screw 28. Such auxiliary fastening devices are shown in Fig. 4, in which it will be observed that set-screws 30 and 30^a are entered through the sides of the body, the former to an engagement with the head of the square blade or arm, the latter, being beneath the said head, serving to draw the slot together, as shown in Fig. 3.

Under such a construction of tool it is obvious that by its use the level of any piece of work may be obtained, whether the face to be leveled is perpendicular or is of greater or less inclination, since the ring-casing containing the level-glass may be turned in the body of the tool until the desired inclination of said glass is obtained.

It is, furthermore, evident that a level is rendered much more effective by the addition of the square arm or blade and its adjusting device, since a square will always be at hand and the blade can be placed at any angle relative to the body in which it is pivoted, as occasion may demand.

Having thus described my invention, I claim as new and desire to secure by Letters Patent—

1. The combination with a plumb or level provided with a vertical recess near one end, of a rotatable ring-casing in said recess, a level-glass in said ring-casing and bent upon itself to form several members at angles to one another, the said members all appearing at the same time at the opening in the ring-casing, a spring held across said recess above the said ring-casing and arranged to engage with said ring-casing, and means operated from the exterior of the tool for binding said spring upon said ring-casing to hold the same

in adjusted position, as and for the purpose specified.

2. A plumb or level provided with a rotatable ring-casing in the body thereof, a level-glass in said ring-casing, a spring engaging 65 with the upper portion of the ring-casing, a guide-bar and face-plate located over said spring and an adjusting-screw inserted through said face-plate and working in a threaded opening in said guide-bar, said screw 70 being arranged to bind said spring upon the said ring-casing, as specified.

3. A plumb or level provided with a ring-casing mounted to turn in the body thereof, having a level-glass bent upon itself to form 75 several members at angles to one another, the various members appearing at the opening in the ring-casing, a spring engaging with the upper portion of the ring-casing, a guide-bar located above the spring, having a threaded 80 opening, a face-plate located above the guide-bar, and an adjusting-screw held to turn loosely in the face-plate, being passed through the threaded opening in the guide-bar to an engagement with said spring at a point above 85 the ring-casing, as and for the purpose specified.

4. In a plumb or level, the combination with the body portion of the tool, of a square blade or arm having a polygonal head pivoted with 90 in a slot in said body, a spring pivoted in said recess near its inner end and engaging with the said head, an exteriorly-operated tension device arranged to engage said spring between its pivot and its contact with the head, and a 95 locking device operated from the exterior of said tool and engaging with said spring at a point directly below the said polygonal head, as specified.

5. In a plumb or level, the body whereof 100 has a longitudinal slot therein, a square blade or arm having a polygonal head pivoted in said slot, a spring pivoted in said body near the inner end of said slot and having its free end 105 engaging with the polygonal surface of said head, two set-screws entered from the lower edge of the body one of which engages said spring between its pivot and its contact with said head and the other of which engages the spring directly below its point of contact with the said head, and auxiliary binding devices located in the sides of the body and arranged for engagement with the sides of the arm and its head and also arranged to draw the walls of the slot together, as and for the purpose 115 specified.

WILLIAM MOORE.
